UNITED STATES PATENT OFFICE.

WILLIAM SELLERS, OF PHILADELPHIA, PENNSYLVANIA, ASSIGNOR TO THE
EDGE MOOR IRON COMPANY, OF DELAWARE.

FURNACE FOR HEATING METALS.

SPECIFICATION forming part of Letters Patent No. 429,776, dated June 10, 1890.

Original application filed March 11, 1887, Serial No. 230,558. Divided and this application filed May 16, 1888. Serial No. 274,072. (No model.)

To all whom it may concern:

Be it known that I, WILLIAM SELLERS, of the city and county of Philadelphia, in the State of Pennsylvania, have invented certain new and useful Improvements in Furnaces for Heating Metal and in the Appliances for Charging and Discharging the Same, of which the following is a specification.

As these improvements were first designed for use in connection with annealing-chambers, I have represented in the drawings and described in the specifications such furnaces and annealing-chambers with their charging and discharging apparatus, the improvement in the art of annealing effected thereby forming the subject-matter of another application now on file in the United States Patent Office; and I do hereby declare the following to be a full and exact description of said furnaces, annealing-chambers, and charging and discharging apparatus, reference being had to the accompanying drawings, forming part of this specification, in which—

Figure 1, Sheet 1, is a plan with one-half in section on the line L M. Fig. 2, Sheet 1, is a side elevation with one-half in section on the line I K. Fig. 3, Sheet 2, is an end view in section on the line A B. Fig. 4, Sheet 2, is an end view of the furnace-chamber in section on the line C D. Fig. 5, Sheet 2, is an end elevation of one-half of the complete furnace, showing a section of the cooling area on the line G H and a section of the downtake and chimney-flue on the line E F. Fig. 6, Sheet 3, is a sectional plan showing the relative position of the several devices for opening and closing the heating-chamber and the annealing-chamber and charging and discharging both chambers. Fig. 7, Sheet 4, is a partial elevation on the lines N O of Fig. 6. Fig. 8, Sheet 4, is a section on the lines P Q of Fig. 9, showing the detail of apparatus for raising and lowering the charge preparatory to and subsequent to its transmission and the apparatus of transmission. Fig. 9, Sheet 4, is a section on the line R S of Fig. 6, showing details of the apparatus of transmission. Fig. 10, Sheet 4, is a section on the line T U of Fig. 6, showing the detail of apparatus for open-

ing and closing the annealing-chamber; and Fig. 11 is a partial elevation on the line V W of Fig. 6, showing the details of apparatus for raising and lowering the charge and the position of the prime mover vertically. Fig. 12, Sheet 4, is an elevation of one end of the furnace, showing in section one of the four hydraulic cylinders and pistons which raise and lower the cover and its connection therewith.

It is well known that in the manufacture of steel castings, particularly in those of considerable weight, that an important molecular change is effected by subjecting such castings to an equable heating at a bright-red temperature and to a uniform cooling, and that this change results in important additions to the ultimate strength and ductility of the metal while imparting to it greater uniformity in these particulars throughout the mass. It is also well known that all forgings of steel in which the whole mass is not finished at a uniform heat will be subject to internal strains, which are liable to result in fracture from trivial shocks, and as it is difficult in most cases and impossible in many to finish such forgings at a uniform heat it is the recognized rule to subject all to an annealing operation—that is, to heat them evenly in an open fire to a red heat and then embed them in hot ashes or other non-conducting material which will exclude the air or prevent its circulation, or to heat them in a furnace and allow them to cool off slowly with the furnace in which they were heated. The former is objectionable by reason of the difficulty in procuring a uniform heat, which is only possible with small objects, and the uniformity of the cooling is uncertain, while the latter, although it effects great uniformity in cooling, involves a great loss of heat, because both metal and furnace must cool off together, and the heat of the furnace must be restored with the next charge. It involves a great loss of time, because the furnace cannot be used for heating a second charge until the first has been cooled off and withdrawn. It involves additional plant, because additional furnaces are required to compensate for such intermittent heating, and these require larger space to

contain them. It must be observed that there is a radical difference between the cooling operations in these two systems. In the first the air is excluded or its circulation is impeded as far as possible. In the second the uniformity of temperature is maintained throughout the closed heating-chamber by a free circulation of the heated gases within this chamber after the furnace is closed to the external air, while the reduction of temperature is effected by conduction to the external air through the outer wall of the heating-chamber and by radiation from the outer surface of these walls.

15 In the practice of the art of annealing steel castings and steel forgings, in which latter I include all wrought-steel, I have discovered that it is not always necessary, and often-times not useful, to prolong the cooling, as 20 in the case where the furnace and its contents are cooled off together. For wrought-steel what is generally required is uniform cooling, and it is only requisite to prolong the cooling to effect its uniformity, and when the 25 metal has a nearly uniform cross-section the cooling may be accelerated with improvement to the quality of the metal. This points to a separation of the heating and cooling chambers for annealing purposes, and my invention comprehends such a separation and also 30 improvements in both heating and cooling chambers and the mode of charging and discharging the same. The advantages of the improved cooling-chamber cannot be availed 35 of except in conjunction with a heating-chamber; but my improved heating-chamber and the devices for charging and discharging the same may be used, and I contemplate using them for heating purposes alone with- 40 out any connection with an annealing-chamber.

It is one object of my present invention to provide a heating-chamber which can be charged and discharged without the use of 45 doors; and it is a further object to provide a means for opening and closing the heating-chamber which shall be simple in construction and easy to operate.

It is a further object to open and close the 50 heating-chamber, so that this chamber may be charged and discharged from either side at will.

It is a further object to provide a means for 55 opening and closing the heating-chamber which shall effect the necessary movement without damage to this chamber, and it is a further object to provide a means for charging the heating-chamber with long bars or plates and discharging the same without dragging them over the hearth of this chamber; and to these ends my invention consists in a 60 heating-furnace provided with a heating-chamber without openings to the surrounding air above the hearth or the supports which 65 sustain the material to be heated, on which hearth the material is heated by the circulation of products of combustion within and

throughout the heating-chamber; and it further consists in a heating-furnace provided with a heating-chamber and a set or series of hinged supports near the plane of the hearth of the heating-chamber, upon which supports the cover, which forms the sides and top of the heating-chamber rocks to open and close the heating-chamber; and it further consists 70 in a heating-furnace provided with a heating-chamber and a set or series of hinged supports upon each side of the furnace and near the plane of the hearth of the heating-chamber, upon either of which supports the cover, 75 which forms the sides and top of the heating-chamber, may rock to open and close the heating-chamber upon either side at will; and it further consists in a heating-furnace provided with a heating-chamber and a set or series of hinged supports 80 near the plane of the hearth of the heating-chamber, upon which supports the cover, which forms the sides and top of the heating-chamber, may rock to open and close the heating-chamber upon either side at will; and it further consists in a heating-furnace provided with a heating-chamber and a set or series of hinged supports 85 near the plane of the hearth of the heating-chamber, upon which supports the cover, which forms the sides and top of the heating-chamber, is rocked by hydraulic cylinders, which have a common supply of pressure-water; and it further consists 90 in a heating-furnace provided with a heating-chamber and a set or series of transferring-racks with means for moving these racks both horizontally and vertically when loaded with 95 the material to be charged to or discharged from the heating-chamber.

In order that my invention may be clearly set forth, I will now describe a furnace embodying my invention, which I have constructed and used in the manufacture of steel eye-bars for bridges and other structures. For the purpose named the furnace must be very long, and it is therefore fired from both ends to obtain a more uniform distribution 100 of the heat, (see Fig. 2, Sheet 1,) in which the grate-bars W are shown clearly in full lines at one end, and the outline of a similar firing-chamber is shown in dotted lines at the other end. The downtake N' is placed midway between the two firing-chambers and connects with the flue leading to the chimney shown by dotted lines passing under the last-mentioned firing-chamber. In order more effectually to obtain a uniform distribution of 105 the heat, each firing-chamber discharges a very small proportion of its gaseous products of combustion into the heating-chamber A' above it. The larger portion of these heated gases enter the flues between 110 the firing-chambers and the downtake N' , and they pass out of these flues through the openings $a a a a$ in the top of the fire-brick covering of these flues and firing-chambers, (see Figs. 1 and 2,) which covering forms the 115 bottom O' of the heating-chamber. As thus arranged, the passage of the heated gases into the heating-chamber may be controlled at will by placing fire-bricks partially or entirely over such of the openings $a a a a$ in 120 which it may be desired to retard or to exclude the delivery of the heated gases; and, lastly, to further facilitate the equal distribution of the heat, I provide the firing-cham- 125

bers with fan-blast or other forced blast, so that the heating-chamber may be worked under a pressure above that of the atmosphere, whereby the heated gases may be forced to 5 any part of the heating-chamber and the oxidizing currents due to a minus pressure may be avoided. To sustain the bars which are to be annealed, I provide rectangular cast-iron hollow supports *b b b b*, the sides of which are 10 perforated with circular openings, (see Figs. 1, 2, and 3,) which supports rest upon the bed or hearth of the heating-chamber *O'*; and to 15 open and close this chamber for the purpose of charging and discharging the material to be annealed, I divide it upon a horizontal plane below the top of the supports *b b b b* and near the plane of the bed or hearth, so that the cover *P' P'*, which forms the sides and top of this chamber, might be removed as 20 a whole at that horizontal plane. This cover is supported in an iron frame-work which can rock or tilt upon the pins *c c*, Fig. 3, and such pins are provided at each of the vertical posts *c' c' c' c'*, on the sides of the furnace. (See Fig. 1.) The corresponding vertical supports for the cover *P' P'* are provided 25 at their lower ends with semi-cylindrical sockets which fit over the pins *c c*, forming, with the sockets, open hinges, upon which the cover 30 may be rocked or tilted in such manner as to open the heating-chamber upon one side or the other at will. This cover is shown by dotted lines in Fig. 3 as tilted to the position for charging the chamber. As thus arranged, 35 the cover of the heating-chamber can be raised by a force but little in excess of half the weight of the cover, and the chamber can be charged and discharged from either side in the plane of its bed. When the chamber 40 is to be charged and discharged from one side only, the cover may be counterbalanced, so as to still further reduce the force required to raise it. I have availed myself of the iron framing which is required to support the 45 cover when tilted, as shown, to support the corrugated iron roof which protects the furnace and its machinery from the weather.

To tilt the cover *P' P'*, I provide two hydraulic cylinders *Q' Q'* at each end of the 50 furnace. (See Figs. 1, 5, 6, and 7.) The axes of these cylinders are inclined, and their pistons and piston-rods are connected to the ends of the beams *R' R'* by the pins *x*, Fig. 5, and are arranged to vibrate in the cylinders, to 55 accommodate themselves to the curve in which the ends of the beams *R' R'* will move as they are raised from one side or the other. The cover of the cylinder *Q'*, Fig. 12, rests loosely upon the ends of the cylinder, and the piston- 60 rod, sliding freely through the cover, causes it to move back and forth across the cylinder with the vibration of the piston-rod. The piston itself is not cylindrical, but rather a section of a sphere provided with the usual 65 hydraulic packing. The vibration of the piston is so slight that the packing is sufficient to accommodate it. High-pressure water

from an accumulator or other supply is admitted by a valve to the two cylinders on the side it is desired to raise or open. The weight 70 of the cover is sufficient to close it when the exhaust-valve is opened and the water is permitted to escape from the cylinders. In raising and lowering this cover upon either set of hinges it is important that the under side 75 of the cover on its open side should be maintained parallel to the bottom of the heating-chamber, as otherwise it would be twisted and its brick work would fall to pieces. If 80 mechanical force was employed for this purpose, some devices for maintaining the cover in position when raised, as also some squaring devices to maintain its parallelism while raising, would be required; but by the use of the two hydraulic cylinders operated from 85 the same source of supply and through one valve further devices than the hinged supports for maintaining the cover in position when raised or its parallelism while raising are not required. 90

To charge and discharge the materials to be annealed, I provide on each side of the furnace a series of wrought-iron frames *d d d d*, the top of each one of which is composed of a pair of rectangular bars riveted together 95 upon interposed thimbles to receive and to support the material as it comes to the furnace and as it is discharged therefrom. The thimbles between these top bars are about one and one-half inches in length and six 100 inches apart to afford convenient fulera for the hand-levers which move the material to its proper position. On the discharging side the top rail is divided into two, for a purpose hereinafter described. (See Figs. 1, 2, 3, and 105 5.) Between these wrought-iron frames I provide on each side of the furnace pairs of cast-iron boxes *s s s s*, each one of the pair set opposite to the other, so as to work together, as hereinafter described, and these 110 boxes are provided at each end with a vertically-sliding frame or box *e e e e*, which carries a roll upon its upper end, having its axis parallel to the side of the furnace, and a roller at its lower end, having its axis at right angles to the side of the furnace. These lower 115 rollers rest upon inclined planes *i i i i*, Figs. 2, 3, 5, 8, and 9, which are secured to and are carried upon the channel-bars *m m m m*, which bars extend the whole length of the 120 furnace, and are supported upon rollers having their axes fixed in the boxes *s s s s* at right angles to the furnace. The two channel-bars on one side of the furnace are united together by the cross-bracing *T'* and *T''*, Fig. 6, and are attached to the piston-rod of the hydraulic cylinder *Z*, Fig. 6, by the cross-bracing *T'*, and a similar cross-bracing connects the two other bars. These 125 two sets of channels are connected together 130 by the lever *U'*, which vibrates about the pin *n* in the end of the iron framing of the furnace, (see Fig. 1,) so that the two sets of channel-bars on the opposite sides of the furnace

when moved must move in opposite directions. The inclined planes *i i i i* are secured to these channel-bars, so that when moving in opposite directions they will raise or lower 5 the boxes *e e e e* on both sides of the furnace simultaneously by means of the rollers in the lower ends of these boxes resting upon the inclined planes. (See Fig. 8.)

The inclined planes *i i i i* are provided with 10 horizontal surfaces at their larger ends, so that when the rollers on the bottom of the boxes *e e e e* are raised or lowered by the inclined surfaces they will rest upon these flat surfaces or upon the channel-bars, for which 15 purpose the channel-bars *m m m m* have a greater movement than the length of the inclines *i i i*.

I have shown and described the raising device as a series of inclined planes, these being 20 the simplest in form and perhaps the least liable to get out of order; but other well-known mechanical devices—such as screws or toggle-joints—may be substituted, or the lifting may be done with hydraulic jacks under 25 each of the vertically-sliding frames or boxes *e e e e*, all of the hydraulic jacks being connected to one supply-pipe and to one discharge-pipe, so as to be operated by one valve. The upper rollers in the boxes *e e e e* next the 30 furnace on each side are supported and turned by the shafts *W' W'*, resting in bearings upon the tops of the boxes *e e e e*, which, for the purpose of being turned with facility, are provided with the hand-wheels *p p p p*, Figs. 1, 35 2, and 5. The rollers on these shafts are gear-pinions shrouded, the shrouding being wide enough to support the weight, while the gear-pinions impel it, as hereinafter described. (See Figs. 8 and 9.)

40 For the purpose of supporting and moving the materials into and out of the heating-chamber, I provide a series of transferring-racks *t t t t*, Figs. 8 and 9, having a length at least sufficient to cover three rollers—that is 45 to say, to cover two rollers on one side of the furnace and to extend across and through the lower edge of the cover of the heating-chamber far enough to rest upon the roller on the opposite side of this chamber, for which 50 purpose openings *r r r r* are provided in the sides of the heating-chamber. These racks are composed of two rectangular bars of iron having a cast-iron rack suitable for meshing with the pinions on the shafts *W' W'*, riveted 55 between them. The openings *r r r r* are provided with vertically-sliding covers, which can be readily raised to admit the racks.

The annealing-chamber *B'* has about the same capacity as the heating-chamber. The 60 cover *X* is composed of plate-iron riveted together and stayed with angle-irons to give it sufficient stability to be hoisted and lowered, and when the chamber is being charged and discharged and when lowered to place is supported in a channel-groove extending all around the base and filled with sand. The bottom is composed of plate-iron, riveted to

the channel-groove and supported from the wrought-iron frames *d d d d*. Openings through this bottom are provided to admit 70 the outer row of boxes *e e e e*; but as these openings are the only ones into this chamber no circulation of air can occur through them, and, moreover, they are provided with close-fitting covers to protect the rollers in the top 75 of the boxes *e e e e*, when lowered to place, from the heat of the cooling mass in the annealing-chamber. The cover *X* when raised is suspended at two points by chains passing over the pulleys *Y Y* and the top of the heating-chamber down to and under other similar pulleys *y y'* on the sides of the boxes *s s*, (see Fig. 7,) from whence they go around similar pulleys *y y'*, carried by the cross-bracing *T' T'*, and from thence to the sides of the boxes 80 *s s*, where they are attached. The movement of the channel-bars, carrying with them the lower pulleys, will move the cover double the distance traversed by the channel-bars, and when raised the cover may be maintained in 85 this position by passing keys through the chain-links below the pulleys on the sides of the boxes *s s*, and the channel-bars may be operated thereafter to perform any of their other functions.

I have described the cover *B'* as of plate-iron, but it may be made of fire-brick as well, and I contemplate making it so whenever it is requisite to prolong the cooling beyond what can be readily accomplished in the plate-iron structure. The time of cooling in the plate-iron structure, however, may be greatly modified by varying the thickness of the metal, or the plates may be double, with an air-space between them, and the width of this 105 air-space may be less or more, or the plates may be covered with asbestos or other refractory felting, any one of which modifications will affect the rapidity with which the heat of the air within the chamber can be transmitted to that exterior to it without affecting the uniformity of its transmission, and such modifications will consequently affect the rapidity of the circulation of the air within the chamber and its cooling effect.

110 It is possible that with very great irregularities of section in the metal to be annealed it may be desired to accelerate or to retard the cooling of certain sections of the annealing-chamber, which can be effected by modifying the structure of any part of this chamber, as above indicated. I prefer, therefore, to use the plate-iron annealing-chamber, not only because its cooling properties can be readily modified, but because it is lighter and 115 can be more easily transported than a fire-brick chamber.

In practicing the art of annealing I have discovered that at least for certain classes of work it takes much longer to cool the metal 120 to be annealed than it does to heat it, and under such circumstances I provide two or more annealing-chambers mounted upon wheels or otherwise arranged, so that each

chamber can be in turn brought up to the heating-chamber to be charged and then transported to some other locality to cool and to be discharged.

- 5 The furnace shown and described having been built for annealing eye-bars, and such a bar being shown supported in position in the heating-chamber, (see Fig. 2,) I will now describe the operation of charging and discharging such bars, which are first assembled on the charging side and arranged edgewise—that is, with their flat sides vertical. Distance-pieces are placed between to permit a free circulation of hot gases around each bar.
- 10 They are bolted together through the holes in the eye to maintain this position and rest on the wrought-iron frames *d d d d*, so that the center of gravity of the mass of bars will fall just inside the outer set of rollers—that is, between these rollers and the annealing-chamber. The boxes *e e e e* are now in their lowest position, and the racks are passed under the mass of bars and over the rollers, and so that the end of the racks will mesh with the pinions on the shaft *W'*. The rollers are now raised by admitting the high-pressure water to the cylinder *Z*, which actuates the channel-bars *m m m m*, by which operation the load will be transferred from the wrought-iron frames *d d d d* to the racks *t t t t*. The cover *P' P'* of the heating-chamber is now raised to the position shown by dotted lines in Fig. 3, and then, by turning the hand-wheels *p p p p*, the mass of bars will be carried into the heating-chamber over the cast-iron hollow supports *b b b b*. When in this position, a rectangular bar of iron *u*, that will pass freely between the wrought-iron supports *d d d d*, is now laid on top of each cast-iron hollow support *b b b b*. The channel-bars *m m m m* are then moved in the opposite direction, which will lower the mass of bars upon the rectangular bars resting upon the top of the cast-iron supports. The racks may then be withdrawn and the cover lowered to the position shown by the full lines in Fig. 3. As soon as the mass of bars has acquired the proper heat the cover should be tilted in the opposite direction, the racks inserted as before, but from the opposite side, then raised upon the rollers, so as to transfer the load upon the cast-iron supports to the racks. The rectangular bars upon the top of the cast-iron supports *b b b b* should then be transferred to the wrought-iron supports *d d d d* in the annealing-chamber and placed between the two bars, of which each of these supports is composed, so as to rest upon the thimbles. The heated mass may then be run out over the wrought-iron frames on the discharging side and lowered upon the red-hot rectangular bars just transferred from the heating-chamber to these frames, and the racks can then be withdrawn. The cover *P' P'* of the heating-chamber is now lowered into place. The covers on the bottom of the annealing-chamber are then placed over the
- 15 outer row of boxes *e e e e*, and the cover *X* of the annealing-chamber is lowered to its position in the channel-grooves, the sand 70 in which makes it air-tight, and in this position it remains until the bars are sufficiently cooled to be removed. In the meantime another charge of bars may be placed in the heating-chamber. The rectangular bars 75 which are placed upon the top of the cast-iron supports in the heating-chamber serve a twofold purpose. The space which they occupy upon the top of the supports affords ample clearance for the mass of material which 80 is being transferred to the heating-chamber and avoids the necessity, which otherwise would exist, of lowering this material to the level from which it started; but their main object is to provide a support to this material 85 in the annealing-chamber having a temperature equal to that of the metal which is to be annealed, so as thereby to avoid a local cooling, which would frustrate the object for which the annealing is resorted to. The bars 90 may be removed from the annealing-chamber with safety before they are cool enough to handle, and to facilitate this operation the wrought-iron frames *d d d d* are extended beyond the annealing-chamber, and when the 95 cover *X* of this chamber is raised a bridge is thrown across the opening between the two top rails of the frames *d d d d*, the bars are disconnected, and they are slid one by one onto the outer end of the wrought-iron frames, 100 from which they may be removed at any time.
- 95 When articles of smaller dimensions are to be annealed, they may be placed in cast-iron boxes provided with openings for the circulation of air or on grates which may be charged 105 into the heating-chamber or discharged from the heating-chamber to the annealing-chamber, as above described.
- 100 By the arrangement of heating-chambers hereinbefore described certain advantages 110 are secured in the maintenance of this chamber which at first sight are not apparent—thus, access to the interior is conveniently obtained without the use of doors, which necessarily afford space through which flame 115 and heated gases will escape. The loss of heat is not by any means the most serious loss, for at such points the doors and the adjoining parts of the furnace become over-heated, so that it is impossible to maintain 120 them in proper condition without resorting to water circulation, as is well understood. This is not only expensive in first cost, but also in maintenance, and it absorbs a large amount of heat which otherwise would be 125 available for the charge. The line of opening to my heating-chamber being upon the plane of the bed and horizontal, there is little tendency for flame or heated gases to escape at the joint, and the cost of maintenance is 130 thereby largely reduced, while the economy of heating is promoted. When the chamber is charged and discharged from one side only, the transferring-racks may be used as anti-

levers, and but one shaft with its pinions to gear into the transferring-racks will be required for charging and discharging the heating-chamber only, and if the vertical movement of this shaft is sufficient the charge may be transferred to the annealing-chamber with this one shaft; but when the charge must be transferred to the annealing-chamber it will generally be more convenient to use two shafts 5 with pinions gearing into the transferring-racks, and they should be arranged so that both shafts can be raised and lowered simultaneously or alternately to suit the character of the work required of them, all of which 10 will be readily understood by any skilled mechanician.

I have filed two applications, of which this is a division of one, for processes in the art of annealing steel castings and steel forgings, 15 said application being serially numbered 230,558 and 284,901, filed March 11, 1887, and September 8, 1888, respectively.

I do not intend to claim in this application the improvement in the art of annealing steel castings or forgings which consists in first heating such casting or forging in a suitable furnace to an equable and proper temperature throughout the mass; then transferring such heated metal into an annealing-chamber, 20 from which the surrounding air and the heated gases of the heating-furnace are excluded when this chamber is closed; then closing this chamber; then recharging the heating-furnace with other metal to be heated and annealed; then replacing the charged annealing-chamber with another similar one not charged, the number of annealing-chambers being so proportioned to the heating-capacity 25 of the heating-furnace that the heating-chamber may receive heat, and discharge the metal to be annealed consecutively and continuously. Nor do I intend to claim in this application the improvement in the art of annealing steel castings and steel forgings which consists in first heating castings or forgings in a suitable furnace to an equable and proper temperature throughout the mass; then transferring such heated metal into an annealing-chamber, 30 from which the surrounding air and the heated gases of the heating-furnace are excluded when this chamber is closed, and then closing this chamber so that the heated metal

within it shall be cooled by the circulation of the air within this chamber. Nor do I intend to claim in this application the improvement 55 in the art of annealing steel castings and forgings which consists in supporting the castings or forgings to be annealed upon heated supports within the annealing-chamber, which chamber is cooler than said heated supports. 60 Nor do I intend to claim in this application the improvement in the art of annealing steel castings and steel forgings which consists in heating the articles to be annealed in an annealing-chamber and regulating the heat-conducting capacity of the walls of said chamber, so that all parts of said casting or forging shall be uniformly and properly cooled, 65 as all of the above form subject-matter of the two applications specifically mentioned 70 above.

What I claim as new, and desire to secure by Letters Patent, is—

1. In a heating-furnace, the combination, 75 with a hearth provided with a flue connected to the chimney, of a cover forming the sides and roof of the heating-chamber, provided with feed-openings below the sides of such cover for the admission and discharge of the materials to be heated, substantially as described.

2. In a heating-furnace, the combination, 80 with a hearth provided with a flue connected to the chimney, of a cover forming the sides and roof of the heating-chamber, provided with feed-openings below the sides of such cover and bearings near the level of the hearth, on which said cover can be rocked, with means for tilting the same.

3. In a heating-furnace, the combination, 85 with a hearth provided with a flue connected to the chimney, of a cover forming the sides and roof of the heating-chamber, provided with feed-openings below the sides of such cover and bearings near the level of the 90 hearth, on which said cover can be rocked with hydraulic cylinders that have a common supply of pressure-water operating through one valve for tilting the cover, substantially as described.

WM. SELLERS.
